UNITED STATES PATENT OFFICE.

GEORGE A. HARPER, OF OIL CITY, PENNSYLVANIA.

WELL-PUMPING APPARATUS.

1,150,188.

Specification of Letters Patent. Patented Aug. 17, 1915.

Application filed February 18, 1915. Serial No. 9,116.

To all whom it may concern:

Be it known that I, GEORGE A. HARPER, a citizen of the United States, residing at Oil City, in the county of Venango and State of Pennsylvania, have invented certain new and useful Improvements in Well-Pumping Apparatus, of which the following is a specification, reference being had to the accompanying drawings.

This invention comprehends certain new and useful improvements in well pumping apparatus or rigs and relates particularly to that class of pumping jacks for oil and other wells wherein a pivoted bell crank lever is operatively connected at one end to the polish or pump rod and at the other end with an engine or motor for the purpose of working the pump mechanism.

To those familiar with the art to which this invention appertains, it is well known that difficulties have been experienced in the use of the ordinary sills or beams between and on which the bell crank lever or jack is fulcrumed, owing to the fact that either one or both of the beams or sills will have a tendency to become more or less displaced in the operation of the rig, whereby the desired direct line of pull of the operating rod leading to the engine or motor will be destroyed by the skewing of the jack support, with the result that the sidewise or lateral strains thus imposed on the jack and its bearings will soon overcome the stability thereof and partially or completely wreck the pumping mechanism.

With a knowledge of these conditions, my invention has for its primary object a simple, durable, and efficient construction of support for the jack, said support being capable of adjustment whereby it may be properly lined up, as required, and thus maintain the plane of movement of the jack coincident with the plane of movement of the jack operating rod. That is to say, the parts are so constructed and arranged that the support may be easily adjusted whenever required so that a line drawn through the polish or pump rod and through the plane of movement of the operating rod will also pass directly through the plane of movement of the jack itself. Hence all liability of wrecking the rig by faulty alignment is positively precluded.

The invention has for its further object an improved construction and arrangement of parts in an apparatus of this kind, in-

cluding laterally and independently adjustable blocks between which the jack or bell crank lever is fulcrumed, whereby it is not only possible to shift the position of the jack itself, as required to properly align the same, but by separating the blocks more or less the support can be used with jacks of varying thickness. And the invention also aims to generally improve devices of this class so as to render them more useful and commercially desirable.

With these and other objects in view, as will more fully appear as the description proceeds, the invention consists in certain constructions, arrangements and combinations of the parts that I shall hereinafter more fully describe and claim.

For a full understanding of the invention, reference is to be had to the following description and accompanying drawing, in which,

Figure 1 is a side elevation of a portion of a pumping rig embodying the improvements of my invention, a number of the parts being shown conventionally and for the purposes of illustration. Fig. 2 is a top plan view with parts in section and other parts broken away. Fig. 3 is a detail transverse sectional view, the section being taken on the line 3—3 of Fig. 2. Fig. 4 is a bottom plan view of the base for the blocks between which the jack is journaled or fulcrumed. Fig. 5 is a transverse sectional view through the beam and a portion of the jack, showing a strut or link member operatively connecting the beam and jack together.

Corresponding and like parts are referred to in the following description and designated in all of the views of the accompanying drawing by like reference characters.

Referring to the drawing, the numeral 1 designates a well platform, 2 a conductor, 3 a polish rod working within the casing, and 4 the pump jack, the latter being operatively connected to the beam 5 by a strut or link member 6, as shown, and the beam being pivotally mounted near one end, as at 7, to swing in a vertical plane between upwardly converging and obliquely disposed supporting rods 8 to which braces 9 are connected.

10 designates an adjuster carried by the beam 5 and through which the rod 11 passes, said rod being connected to the polish rod 3, and 12 designates the jack operating rod which leads to an engine or motor or any

other prime mover whereby a horizontal reciprocating movement will be imparted to the rod 12, a rocking movement imparted to the jack 4, and a swinging movement to the beam 5 so as to properly operate the polish rod 3.

All of the parts hereinbefore specified may be of any desired or conventional construction and design, and are here shown for the 10 purposes of illustration only so that my invention embodied herein may be fully understood.

The jack 4 is fulcrumed at its elbow on a transversely disposed rod or spindle 13 and 15 is received between supporting blocks 14 mounted upon a base 15 which may be formed either as a casting or out of sheet metal or otherwise, as desired. The blocks 14 have vertically disposed bolts 16 passing 20 therethrough, said bolts being also received in transversely elongated slots 17 formed in the base 15, as best illustrated in Figs. 3 and 4, and the base itself is preferably formed at each end with an arcuate slot 18, 25 said last named slots receiving bolts 19 which are in the nature of set screws which extend down into the platform 1. It is to be understood that it is within the purview of my invention to dispense with the arcuate 30 slots and bolts 19, and that the invention is not limited thereto in any respect.

Each of the blocks 14 is bored horizontally in a slightly oblique direction to receive two rearwardly diverging link rods 20 on which 35 adjusting nuts 21 are screwed, and the forward ends of the rods 20 are pivotally connected to a collar 22 which encircles the conductor 2, as clearly illustrated in Figs. 1 and 2.

40 From the foregoing description in connection with the accompanying drawing, the operation of my improved jack support will be apparent. In the practical use of the device, whenever it is necessary to properly 45 line up the jack, all the operator has to do is to screw up upon the required nuts 21 on the rods 20 to angularly shift the position of the base 15 and bring the entire jack support into such a position on the platform as 50 to secure the correct alinement of the jack; or, if required, the blocks 14 themselves may be shifted laterally in one direction or the reverse upon the base 15 to secure the required alinement. Furthermore, it will be 55 understood that as these blocks 14 are independently movable or adjustable, they may be brought nearer to, or farther away, from each other in order to accommodate jacks of varying thicknesses or widths.

60 It will thus be seen that I have provided a very simple, durable and efficient construction of jack supporting apparatus for well rigs or pumping mechanism by the use of which the jack may be at all times maintained in proper alinement, as set forth at 65

the outset of the specification, and that the parts are few in number and of such a construction that they can be easily made and assembled and not liable to get out of order or require any especial attention.

70 Preferably, the bearing plates 23 for the spindle or shaft 13 are formed with upstanding lugs 24 to which the lower ends of the brace rods 9 are bolted or otherwise connected.

75 While the accompanying drawing illustrates what I believe to be the preferred embodiment of my invention, it is to be understood that the invention is not limited thereto, but that various changes may be made 80 in the construction, arrangements and proportions of the parts without departing from the scope of the invention as defined in the appended claims. For example, I wish it to be distinctly understood that the invention 85 is not limited to having the blocks separate from the base, but that the blocks may be formed integral or solid with the base, and in the following claims, where the blocks and base are mentioned separately, it is to 90 be understood that this does not necessarily mean that the blocks are parts separate and distinct from the base and secured thereto, for they may be just as well formed therewith. Furthermore, I consider it to be within 95 the scope of my invention to do entirely away with the base 15 as a separate element, particularly in those cases where it is not desired to have the blocks disposed toward and from each other in order to accommodate 100 the spaces therebetween for jacks or bell cranks of different widths.

95 What is claimed, is:

1. In a pumping mechanism of the character described, the combination with a conductor and a jack, of a support for the jack, said support including blocks, rearwardly diverging rods passing through said blocks and operatively connected at their forward ends to the conductor, and nuts applied to 105 the rods and bearing against the opposite faces of the blocks, for the purpose specified.

2. In a well pumping apparatus of the character described, the combination with a 115 conductor and a jack, of a collar encircling the conductor, rods connected at one end to said collar and extending over same in diverging relation to each other, blocks between which the jack is fulcrumed, the rods 120 passing through said blocks, and means for adjusting the rods relative to the blocks.

3. In a well pumping apparatus of the character described, the combination with a conductor and a jack, of a collar encircling 125 the conductor, rods connected to said collar and diverging therefrom, blocks between which the jack is fulcrumed, the rods passing through said blocks, means on the rods for adjusting the blocks on the same, bolts 130

carried by said blocks, and a base on which the blocks are mounted, said base being formed with laterally elongated slots and the bolts being disposed in said slots.

- 5 4. In a well pumping apparatus of the character described, the combination with a conductor and a jack, of a collar encircling the conductor, rods connected to said collar and diverging therefrom, blocks between 10 which the jack is fulcrumed, the rods passing through said blocks, means on the rods for adjusting the blocks on the same, bolts carried by said blocks, and a base on which

the blocks are mounted, said base being formed with laterally elongated slots and the bolts being disposed in said slots, said base being further formed near each end with arcuate slots and bolts embodied in said slots and adapted to be connected to the platform, as and for the purpose set forth. 15

In testimony whereof I hereunto affix my signature in the presence of two witnesses.

GEORGE A. HARPER.
